UNITED STATES PATENT OFFICE.

JABEZ H. GILL, OF PHILADELPHIA, PENNSYLVANIA.

MACHINE FOR HEADING CARTRIDGE-SHELLS.

SPECIFICATION forming part of Letters Patent No. 241,962, dated May 24, 1881.

Application filed March 10, 1881. (No model.)

To all whom it may concern:

Be it known that I, JABEZ H. GILL, of Philadelphia, in the county of Philadelphia and State of Pennsylvania, have invented certain 5 Improvements in Machines for Heading Cartridge-Shells, of which the following is a specification.

My invention relates to machines for heading cartridge-shells; and the invention consists in 10 a novel manner of constructing the frame and mounting the crank-shaft therein; and, second, in a novel manner of securing the heading punch or bunter, all as hereinafter more fully described.

15 Figure 1 is a longitudinal vertical section, on the line α α of Fig. 2, of the frame of my improved heading-machine. Fig. 2 is a top-plan view of the same; and Fig. 3 is a sectional view of a portion shown detached to illustrate 20 the manner of securing, adjusting, and supporting the heading punch or bunter.

Originally metallic cartridges were made of comparatively thin metal, and had their heads formed by folding the metal back upon itself 25 to produce the radial flange. Subsequently the head or flange was formed by compressing the solid metal in such a manner as to cause it to flow outward around the edge of the head and thereby produce a solid head without fold 30 or seam. This operation requires a very strong pressure, and consequently the machines are made much heavier and stronger than for the folded heads formerly manufactured.

Of late thicker and heavier metal has been 35 used to produce these solid-headed shells, and experience has demonstrated that the machines as ordinarily made will not stand the required pressure and remain in order so as to work with the desired degree of accuracy.

40 One source of difficulty is the yielding of the crank-shaft, which operates the heading punch or bunter, when mounted in boxes in the usual manner. For however nicely these boxes may be fitted to the frame and the shaft it is found 45 that the shaft and its boxes will yield more or less, and when subjected to the great pressure required the machine, for that reason, will not operate with the degree of accuracy required to form the solid heads with perfect uniformity, especially when these heads are formed 50 in a countersunk or recessed die, in which case

sufficient pressure is applied to squeeze a portion of the metal of the head out around the end of the punch.

Another difficulty with these machines arises 55 from the gradual yielding of the punch or bunter in its seat in the cross-head or reciprocating carrier. Even when provided with a screw-thread, by which it is held in the cross-head, it is found that owing to the irregular 60 bearing of these threads the bunter will after a time give more or less, thereby rendering the heads defective by making them of varying thickness.

The object of my present invention is to so 65 construct a heading-machine as to overcome or obviate these difficulties, and thus produce a header that will form these solid heads on shells with accuracy and uniformity.

To obviate the first-mentioned difficulty or 70 defect I make the bed or frame A of the machine in a single solid casting, as represented in Figs. 1 and 2, with vertical sides B, each having an enlargement, E, at the end where the crank-shaft D is mounted. These enlargements 75 or shoulders E are each provided with an opening, I, Fig. 1, of such a size as to permit the crank-shaft D to be shoved endwise through said openings, as shown in Fig. 1 and by the dotted lines in Fig. 2. Then, instead of fitting 80 boxes in the frame for the shaft to rest and work in, I form the bearings for the journals of the shaft D in the solid metal of the frame itself, as shown in Fig. 1, the bearing being made on the side of the shaft opposite that on 85 which the pressure is applied in forming the head, so that when the crank assumes the position shown in Fig. 2 it has its bearing against the solid metal of the frame without any intervening box or piece whatever. 90

In order to hold the crank-shaft in place a half-box, C, is fitted in the opening I on the opposite side of the journals, as shown in Fig. 1, this box being held in place by a clamp or follower, b, provided with a screw-bolt, a, on 95 which there is a jam-nut, c, as shown in Fig. 1. The heading-die is secured about midway of the frame, and to the crank-shaft D is secured a pitman, to the opposite end of which is attached the usual slide or cross-head that carries the heading punch or bunter, these parts not being shown, as they may be made in any 100

desired or usual manner, and do not contain any part of my invention, except as to the manner in which the heading punch or bunter is secured thereto, and which I now proceed to explain.

5 This feature of my invention is shown in Fig. 3, in which J represents the nose or projecting end of the slide which carries the heading punch or bunter, the parts in this, as in Figs. 1 and 2, being reduced in size, this being less reduced than the others, however. The part J has a hole bored in its end, as usual, and is also provided with an internal screw-thread, as shown. The punch P in this case is represented as being inserted in a holder or separate piece, L, though, if preferred, these may be formed of a single solid piece, and in either case the part L is provided with an external screw-thread, O, by which it is adjusted and held in place.

At the inner end of the part L a hole is made transversely through the part J, in which is fitted a wedge-shaped piece, K, of hardened steel, as shown in Fig. 3, so that after the punch 25 or its holder L (in case the latter be used) is adjusted to the exact position required by means of the screw-thread the wedge K is driven in, so as to form a solid bearing for the inner end of the punch or bunter, thus relieving the 30 screw-threads from the great strain and wear to which they would otherwise be subjected.

By these means I am enabled to make a heading-machine that will form solid-headed shells 35 with a degree of accuracy heretofore unattainable, and which will retain its accuracy for a much longer period than when made in the usual manner.

One great advantage of such a machine is that the heads of the shells can be formed in the countersink of the recess of the heading-die, thereby making the body of the head or flange perfectly uniform and concentric with the body of the shell, and saving all the trouble and expense of subsequently trimming the heads, except to remove the thin rim of metal 40 which is formed by the excess of metal squeezed out of the recess in the die, and which, being much thinner than the flange itself, can be easily and quickly removed.

I am aware that it is customary to bore a 50 hole in castings and other metals to form a bearing for spindles or shafts, and that it is not new to unite parts by means of a gib or key passing through holes in the parts thus united, and therefore I do not claim these; but 55 Having fully described my invention, what I claim is—

1. As an improvement in heading-machines, the frame A, provided with the openings I, of suitable size to permit the crank-shaft D to be 60 inserted through the same, with the bearing for said shaft formed in the solid metal of the frame, and devices, substantially such as shown, for holding the shaft in position.

2. The punch or its holder L, fitted to the 65 bunter J, with a screw-thread, O, in combination with the key or wedge K, arranged to operate as and for the purpose set forth.

JABEZ H. GILL.
